UNITED STATES PATENT OFFICE.

ROBERT E. FISHER AND WILLIAM M. YORK, OF LONG BEACH, CALIFORNIA; SAID FISHER ASSIGNOR TO SAID YORK.

PAY-ENVELOP.

1,346,372.

Specification of Letters Patent. Patented July 13, 1920.

Application filed December 16, 1916. Serial No. 137,459.

To all whom it may concern:

Be it known that we, ROBERT E. FISHER and WILLIAM M. YORK, both citizens of the United States, residing at Long Beach, in 5 the county of Los Angeles and State of California, have invented a new and useful Pay-Envelop, of which the following is a specification.

Our invention relates to the art of advertising, and the principal object of the invention is to provide means for building up good-will within a certain group of persons. This means may be embodied in a container in which merchandise, or other 15 material things are placed. While the invention is generally applicable to any sort of a container, its operation can be best understood if a specific form of container is considered, and for this reason we have selected as an illustration a pay envelop shown 20 in Figure 1. We have also shown a pay check in Fig. 2.

It is common practice for employers to place the employee's wages in sealed envelopes, these envelopes containing the exact wages due, so that a large number of employees can be quickly paid without the necessity for making change.

Such a pay envelop is shown, for illustrative purposes only, in the accompanying drawing. It consists of a paper or cloth envelop 11 provided with a sealing flap 12. Marked on the top of the envelop is the employee's name 13, his shop number 14, 35 and the amount of his wages 15. The name 16 of the employer and his address 17 may also be marked thereon. In all of the above particulars the envelop resembles an ordinary pay envelop, and no claim of novelty is 40 made therefor.

Our invention resides in a series of coupons 18 which are formed in the body of the envelop and are preferably divided by perforations 19, so that each can be readily 45 detached. Each of these coupons contains the name, or other designation, of a merchant, professional man, amusement owner, or other person or organization which desires the employee's patronage, and also contains the name of the person using the pay envelop. Each of these coupons is good for 50 a fixed sum, say five cents, on every purchase of over a certain amount, say one dollar, which the employee may make.

The method of operation of the invention 55 is as follows:

The employer or any other person who distributes containers, all such persons being included under the term "distributers," makes a contract with the merchants or 60 other persons who are to redeem the coupons, all such persons being included in the term "redeemers," or such contracts are made through an independent organization known as the "contractors" who receive a 65 percentage of the business handled, or are otherwise reimbursed by either the distributor or the redeemers. The distributor delivers the containers to a group of persons who may be called the "receivers." 70 These receivers may be employees, in the case of the pay envelop, or they may be purchasers of goods or others.

The distributor benefits by the scheme due to each coupon being marked with his name 75 so that the redeemer knows where the money he receives comes from. This creates good-will flowing from the redeemer to the distributor, and this good-will is a real asset to the distributor. The receiver benefits in 80 that each of the coupons represents a bonus which he can avail himself of or not, as he sees fit. The redeemer benefits in that he induces the receivers to trade with him, and especially where a large concern does business in a small town the advantages of this 85 inducement are large. The contractor may also benefit largely in that his only expense is the printing and distribution of envelops and the incidental expenses of making and 90 collection under the contractors.

It is also possible to make the scheme a mutual one, some of the redeemers being in turn distributors so that the business of the receivers is kept within a small circle. For 95 example, a bank may agree to make up the payrolls of a large number of concerns, using envelops on which each concern appears in turn as distributor, and all the others as redeemers.

While our invention is especially adapted to containers, and even more especially to pay envelops, the same general scheme may be utilized in connection with a check as shown in Fig. 2. Here the check is made 105 out to a receiver 51 by a distributor 52, and has attached thereto coupons 53, each of which contains the distributor's name and

the name of a redeemer 54. These coupons are redeemable in the same manner as the coupons 18 and are handled in much the same manner. This check may be a pay 5 check, or it may be a personal or business check. A group of persons may adopt such checks, each person using a check to which are attached coupons of all the other persons. This scheme can also be operated by 10 banks who can furnish checks to a certain group of depositors in which the check of each depositor carries the coupons of all the rest of the group, thus conserving the funds of the group largely within the group. 15 All such modifications, and all improvements and variations thereof, are within the scope and spirit of our invention, which is limited solely by the annexed claim.

We claim as our invention:—

A pay envelop adapted to contain an em- 20 ployee's wages; and a plurality of coupons formed in the body of the envelop, each coupon having plainly marked thereon a symbol identifying a merchant who has agreed to accept same as part payment in 25 trade, and each coupon bearing a symbol serving to identify the employee originally issuing the envelop; said envelop also bearing symbols indicating that said coupons 30 will be accepted by said merchants.

In testimony whereof, we have hereunto set our hands at Los Angeles, California, this 8th day of December, 1916.

ROBERT E. FISHER.
WILLIAM M. YORK.
